UNITED STATES PATENT OFFICE.

RICHARD THURM, OF SAGINAW, MICHIGAN, ASSIGNOR TO BAKER PERKINS COMPANY, INCORPORATED, OF SAGINAW, MICHIGAN, A CORPORATION OF NEW YORK.

TUBULAR BURNER.

Original application filed October 15, 1925, Serial No. 62,511. Divided and this application filed January 31, 1928. Serial No. 250,849.

This invention relates to burners for illuminating gas, producer gas, water gas, vaporized oils and similar fuels, and particularly to the long tubular burners which are used for burning mixtures of gaseous fuels and air in substantially oxygen-free atmospheres as, for example, in baking ovens. When the ordinary long tubular burner supplied with a combustible mixture of air and gaseous fuel is located so that the combustion at its outlets takes place in a more or less confined space in an atmosphere that is substantially free from or at least deficient in oxygen and raised to a comparatively high temperature, there is liability to objectionable and somewhat dangerous back-firing and explosions.

The principal object of the present invention is to provide an improved burner so constructed as to prevent such back-firing and explosions and to insure a continuous and substantially uniform combustion throughout the length of the burner.

With these and other objects in view, the invention comprises the novel and improved features, constructions and combination of parts hereinafter described and particularly pointed out in the claims, the advantages of which will be clearly understood and appreciated by those skilled in the art.

This application is a divisional application based upon certain subject matter contained in a prior application, Serial No. 62,511, filed October 15, 1925, by Richard Thurm and Eugene Oscar Engels.

The invention will be clearly understood from the accompanying drawings illustrating the invention in its preferred form, and the following detailed description of the constructions therein shown.

In the drawings—

Figure 1 is a view in side elevation of a burner embodying the invention showing its arrangement in the chamber of a baking oven and its connection to the means for supplying fuel thereto;

Figure 2 is a vertical sectional view through the burner taken on the line 2—2 of Figure 1;

Figure 3 is a top plan view on an enlarged scale of a portion of the burner; and

Figure 4 is a detail vertical sectional view illustrating certain parts of the burner removed therefrom.

In the illustrated embodiment of the invention, the burner includes a suitable fuel chamber to which combustible fuel is supplied from a suitable conduit which preferably extends substantially throughout the length of the fuel chamber. This conduit is supplied with combustible fuel from a fuel main to which the fuel is supplied from a mixing device which in turn has connection with suitable means for supplying the different elements of which the fuel is composed. From the fuel chamber the fuel is discharged and burned at the point of discharge.

One type of chamber which has proven quite successful in actual operation consists of a tubular member 14 substantially circular in cross sectional form. This tubular member 14 is provided with an elongated opening preferably in the form of a slot 16, the length of which is determined by the length of flame desired. In this type of burner a conduit 15 is employed and this conduit extends preferably throughout the entire length of the chamber formed by the tubular member 14, as indicated by dotted lines in Figure 1. This conduit 15 is of tubular form, semi-circular in cross section and, as shown in Figure 2, is located in the lower portion of the tubular member 14 with its plane wall positioned upwardly, thus providing a fuel chamber 20. Suitable discharge openings, such for example, as the staggered perforations 21, are provided in the plane wall of the conduit 15 and these discharge openings serve to permit the fuel to pass from the conduit 15 into the chamber 20, formed by the tubular member 14 in a manner which maintains a uniform pressure of fuel in the chamber 20. Fuel is supplied to the conduit 15 by means of a suitable pipe controlled by a valve 8 and connected to a combustible fuel supply in the form of a fuel main 7. Combustible fuel is supplied to the fuel main 7 from a suitable mixing

device 9 to which the elements of the fuel are supplied separately in any desired manner.

The fuel is discharged through the elongated opening or slot 16 of the tubular member 14 and is ignited or burned as it issues therefrom. To promote combustion of the fuel it is desirable that its discharge through the opening 16 be partially controlled and to 10 accomplish this result, this opening 16 may be provided with suitable means, which forms a plurality of relatively long passageways through which the fuel passes in its discharge from the tubular member 14.

15 To obtain the aforementioned results a suitable structure is positioned within the elongated opening or slot 16 and this structure preferably comprises two parallel bars or plates 24 which form side walls for the 20 elongated opening and slot 16 as more clearly shown in Figure 2. These side walls are retained in spaced relation by means of a suitable distributing element which in the present instance is shown as a length or strip of wire 25 mesh of substantially the same width as the plates 24 interposed between said plates. This structure, including the plates 24 and the wire mesh spacing and distributing member 25 may be secured together to form a unitary 30 structure by a suitable fastening means such, for example, as rivets 26 arranged in suitably spaced openings 29 provided in the plates which form the side walls, and said plates 24 are maintained in predetermined spaced relation by suitable spacing members 30, which 35 preferably surround the rivets 26.

As shown in Figure 2 this structure is positioned in the opening or slot 16 and is preferably adapted to rest upon bolts 22 which extend transversely of the tubular member 14 and are positioned in suitably oppositely disposed openings therein. It will be noted that the bars forming the side walls 24 are of such a width that they project slightly beyond the outer edges of the opening 16 when they are resting upon the bolts 22. After the bars or side walls 24 have been positioned in the opening or elongated slot 16 nuts 23 carried by the transversely extending bolts 22 are tightened 45 and the tubular member 14 is contracted until the sides of the slot 16 engage their respective side walls 24, and upon further tightening of the nuts 23, the side walls 24 and the wire mesh spacing member 25 will be firmly 50 clamped in position in the elongated opening 16 and the edges of the elongated opening 16 by reason of their contact with their respective side walls 24, will form a gas-tight 55 joint therewith to preclude the possibility of fuel escaping around the outside of the side walls 24.

The unitary structure which comprises the side walls 24 and the wire mesh spacing member 25 may also be retained in the elongated 60 opening 16 by means of end plates 27 which

overlie the ends of the plates 24, said plates being secured to the tubular member 14 as by screws or the like 28 shown in Figure 3, and these end plates 27 are shaped or formed to provide a tight joint at the ends of the elongated slot to prevent the escape of fuel at this point. There is preferably one of these end plates adjacent each end of the elongated opening. If desired, one or more clips such as 70 40 may be employed between the ends of the elongated opening 16, said clips being so formed as to overlie the plates 24 to serve to retain them in position. Each of these clips is secured to the tubular member 14 in any desired manner, a screw 41 being herein 75 shown for this purpose.

By this construction, it will be apparent that the space between the side walls 24 will be divided by the wire mesh member 25 into a plurality of sinuous passages through which the fuel is caused to pass in its discharge from the tubular member 14. It has been found that such a structure, that is, one which discharges the fuel through relatively long 80 passages, gives highly satisfactory results and materially aids in the proper combustion of the fuel at the combustion points.

By varying the mesh of the spacing member 25, the burner is readily adapted to use with fuels of different character, and in this manner also the volume of heat produced by the burner may be controlled.

A burner construction in accordance with the present invention has many wide and varied uses. It is herein shown as a burner for baking ovens and it is to be understood that several of these burners are employed for heating the oven. The burners may be supported from the opposite walls 10 and 11 of the oven, as shown in Figure 1, and between these walls 10 and 11 suitable supports 12 extend transversely of the burners to prevent sagging thereof between their ends.

While I have described a preferred embodiment of my invention, I realize that it may be embodied in widely different forms other than that shown and I, therefore, do not limit myself to the particular construction illustrated and described herein.

What is claimed as new is:

1. A gaseous fuel burner comprising a conduit for gas and the like having an elongated discharge opening therein, and means for controlling the flow of gas through said opening, said controlling means comprising a plurality of check bars extending longitudinally of said opening, and wire mesh interposed therebetween to maintain them in spaced relation, said check bars and wire mesh projecting into the conduit to provide relatively long 115 passages for the fuel.

2. A gaseous fuel burner comprising a conduit for gas and the like having an elongated discharge opening therein, and means for controlling the flow of gas through said open-

ing, said controlling means comprising a plurality of check bars extending longitudinally of said opening, and wire mesh interposed therebetween to maintain them in spaced relation, said check bars and wire mesh being of substantially the same length and width and projecting into the conduit to provide relatively long passages for the fuel.

3. A gaseous fuel burner comprising a conduit for gas having an elongated opening therein provided with walls extending longitudinally thereof, said walls being spaced apart, and a single layer of wire mesh interposed between and engaged by both said walls to provide passages for the fuel.

4. A gaseous fuel burner comprising a conduit for gas and the like having an elongated opening therein provided with walls running longitudinally thereof, said walls being spaced apart, and a single layer of wire mesh of a width substantially equal to the width of the said walls, said walls and wire mesh extending into said gas conduit.

5. A gaseous fuel burner comprising a conduit for gas and the like having an elongated burner opening therein, a pair of check bars mounted in said opening, and a single layer of wire mesh interposed between said check bars and engaged by the inner surfaces of the bars to space the bars and form passages for the fuel.

6. A gaseous fuel burner comprising a conduit for gas and the like having an elongated opening therein, and means for controlling the flow of gas through said opening, said means including check bars mounted in said opening, and a single layer of wire mesh interposed between said check bars, said check bars and wire mesh extending into said conduit to form elongated passages for the fuel.

Signed at Saginaw, Michigan, this 27th day of Jan'y, 1928.

RICHARD THURM.
